SHUTTLE HOLDING MEANS

Kurt Schwabe, Le Locle, Switzerland

Application September 27, 1950, Serial No. 187,067
In Switzerland September 29, 1949

14 Claims. (Cl. 139—241)

1 My present invention relates to a device for holding a shuttle during the changing of the weft bobbin in a loom having a means for automatically changing the weft bobbin.

In looms having a mechanism for automatically changing the weft bobbin, the accurate positioning of the shuttle with reference to the newly exchanged weft bobbin is of the utmost importance in order to obtain the correct position of the new bobbin in the shuttle. In all known looms, the position of the shuttle during the changing of the weft bobbin is determined by engagement of an element with only one portion of the shuttle, that is, only by the picker, whereas any additional means for fixing the position of the shuttle is lacking. The maintenance of an accurate position of the shuttle during the changing of the weft bobbin is therefore not assured, and lack of uniformity in the picking operation influences the position of the shuttle with respect to the weft bobbin. Also wearing out of the operative parts of the machine, as for example, wearing of the picker, results in a changing of the position of the shuttle. These disadvantages are overcome by my present invention.

According to my present invention a device is provided for holding the shuttle during the changing of the weft bobbin in a loom having an automatic means for changing the weft bobbin, and in this device the changing of the weft bobbin takes place outside of the shuttle box. According to the invention, the position of the shuttle is fixed, on the one hand, by a resiliently mounted stop means which absorbs the kinetic energy of the shuttle, and, on the other hand, by means of a stop surface located on the shuttle, the said stop surface cooperating with a pawl which is influenced by a spring, the said pawl coming in contact with the said stop surface upon return movement of the shuttle under the action of the resiliently mounted stop means. In this manner, during the changing of the bobbin, the shuttle is held between the resiliently mounted stop means and the pawl engaging the stop surface on the shuttle.

In accordance with the above considerations, it is an object of my present invention to provide a means for accurately determining the position of the shuttle during the changing of the weft bobbin, the said position being unaffected by any lack of uniformity or wear in the parts of the shuttle operating mechanism.

An additional object of my present invention is to provide a plurality of elements for determining the position of the shuttle during the changing of the weft bobbin.

2 A still further object of my present invention is to provide a loom in which the weft bobbin is changed while the shuttle is located outside of the shuttle box.

3 With the above objects in view, my present invention mainly consists of a device for holding a shuttle during the changing of the weft bobbin in a loom having a mechanism for automatically changing the weft bobbin and in which the changing of the weft bobbin takes place outside of the shuttle box, comprising, in combination, a resiliently mounted stop engaging one end of the shuttle; a stop means mounted on the shuttle; and a pawl engaging the stop means on the shuttle, whereby the shuttle is clamped between said resiliently mounted stop and the pawl so as to fix its position during the changing of the weft bobbin.

4 The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

5 Fig. 1 is a view of one embodiment of my present invention, showing the arrangement of the parts thereof during the changing of the weft bobbin;

10 Fig. 2 is a view of the position of the parts of the machine during the operation of the machine, that is, before and after the weft bobbin has been changed;

15 Fig. 3 is a sectional view on an enlarged scale taken on line 3—3 of Fig. 1;

20 Fig. 4 is a detail view of some parts of the apparatus; and

25 Fig. 5 is a partial sectional view taken on the line 5—5 of Fig. 1.

30 In the embodiment of the machine for carrying out my present invention, as shown in the drawings, the shuttle 1 has an opening in which is located the weft bobbin 2. In the operating position of the loom, as shown in Fig. 2, the shuttle is located within the shuttle box 3, the said shuttle box having four compartments. The shuttle 1 cooperates with a picker 4. Fixed to the shuttle box 3 is the exchange bearing 5 which is mounted so as to be stationary with respect to a picker rail which is not shown in the drawings. After the commencement of the operation during which the weft bobbin is changed, the shuttle and weft bobbin 2 are moved into the exchange bearing 5. Fixedly mounted with respect to ex-

change bearing 5 is the rail 6 which is parallel to the axis of the shuttle and in which a slidable bar 7 is guided. The loom illustrated does not include any exchange box. This exchange box is replaced by the exchange bearing 5 which has a U-shaped cross section providing a rail with which the rail 6 cooperates.

In a cutout portion of slidable bar 7 is slidably mounted the rack 8, which comprises two portions 8a and 8b. The movement of rack 8 with respect to slidable bar 7 is limited by means of projections 25 and 26 on slidable bar 7, the said projections cooperating with the portions 8b and 8a, respectively. On an outer end of slidable bar 7 is fixed a spring housing 9, in which a buffer pin 10 is guided, the said buffer pin 10 cooperating with the picker 4. The buffer pin 10 presses against the spring 11 located within the spring housing 9. The buffer pin 10 is provided with a stop which advantageously is formed by the nut 12 which is screwed onto threads on the end of 20 12 which is screwed onto threads on the end of an extension of buffer pin 10 which extends through an opening at the end of spring housing 9.

A pinion 13 is adapted to engage with and drive the rack 8, the said pinion being mounted on a shaft 14 which is driven by the motor 15, when the changing of the weft bobbin takes place. On the exchange bearing 5 is mounted the pin 16 on which is pivotally mounted the two-armed pawl 17. The upper arm 17' of the pawl, as viewed in Fig. 1, is adapted to extend through an opening in the rail 6 and to engage suitably shaped recesses 29 and 30 in the rack 8 and slidable member 7, respectively, during the changing of the weft bobbin. On the other arm 17" of the pawl 17 is connected one end of the spring 18 which pulls on the pawl 17 so that arm 17 thereof is pressed through the opening in the rail 6.

On the rail 6 there is rotatably mounted another pin 19 to which are fixed a pawl 20 and a two-armed control lever 21. The control lever 21 is located in a cutout portion in the rail 6 and is so arranged that it may cooperate with the portion 8c of the rack 8. One arm of the control 45 lever 21 is engaged by a spring 22 which tends to rotate the control lever 21 and the pin 19 therewith in a counterclockwise direction, as viewed in Fig. 2. This counterclockwise movement of the control lever 21 is limited by the engagement of stop 21a, on the other arm of control lever 21, with the rail 6.

When the weft bobbin changing operation is started, the device for changing the weft bobbin starts the rotation of the motor 15 by any known means. The pinion 13 is thereby driven by the motor 15 and drives the rack 8 to the right, as viewed in Figs. 1 and 2, so that the rack 8 starts to travel from the position shown in Fig. 2 to the position shown in Fig. 1. Just after the commencement of the driving of the motor, elements 7 and 8 pass through the position shown in Fig. 4. At the start of this operation, the inclined surface 8d on the end of rack 8 depresses pawl 17, and upon continued movement of rack 8 projection 25 on slidable bar 7 is engaged by portion 8b of rack 8, so that elements 7 and 8 then move together to the right, as viewed in Fig. 1. The movement of elements 7 and 8 to the right, as viewed in Fig. 1, is limited by the stop 27.

During the movement of rack 8, portion 8c thereof depresses the control lever 21 and in this manner the pawl 20 is correspondingly depressed. When the rack 8 has reached its final 75

position, as shown in Fig. 1, the pawl 20 moves upwardly under the influence of spring 22, since the rack 8 comprises a cutout portion between portions 8b and 8c thereof which permits a corresponding movement of control lever 21.

At this time, by any known means, the shuttle 1 is moved toward the position where the weft bobbin is to be changed, and in this way the picker 4, which is disconnected from its picker rod, is moved ahead of shuttle 1. The pawl 20 is depressed by the movement of the shuttle 1 thereover. The picker 4 then strikes against the head of buffer pin 10 and moves the buffer pin 10 against the action of spring 11 in spring housing 9 until the kinetic energy of the shuttle 1 is absorbed, whereupon the spring 11 then expands and moves the shuttle in a reverse direction, by means of the buffer pin 10 and picker 4.

In the meantime, the pawl 20, under the action of spring 22 has entered a groove 1c in the underside of the shuttle 1. The righthand end of groove 1c, as viewed in Fig. 1, comprises a stop surface 1a which bears against the end of pawl 20. Also, at the end of the movement of elements 7 and 8 to the right, as viewed in Fig. 1, pawl 17 latches with the aligned recesses 29 and 30.

The shuttle 1 therefore is held clamped between the picker and pawl 20, and thereby assumes an accurately determined position.

After the operation of exchanging the weft bobbin 2 has been completed, the direction of rotation of the electric motor 15 is reversed by any known means. In this way, the rack 8 is then moved by means of pinion 13 to the left, as viewed in Fig. 1, whereby the portion 8a of rack 8 engages projection 26 of slidable bar 7 so as to move slidable bar 7 with rack 8.

During the initial return movement of rack 8, the cutout portion 29 of rack 8 depresses pawl 17 so that it is unlatched from engagement with slidable bar 7. Also during this return movement, the pawl 20 is moved out of engagement with groove 1c and stop surface 1a by means of portion 8c of rack 8 which engages control lever 21 so as to depress control lever 21 and pawl 20 therewith.

In this manner, the shuttle 1 can move together with the slidable bar 7 back to its operating position, in which position the slidable bar 7 is latched into position by the engagement of pawl 17 with the inclined end 8d of rack 8 and by engagement of projection 26 with portion 8a of rack 8.

It will be understood that each of the elements described above, or two or more together, may also find a useful application in other types of looms differing from the types described above.

While I have illustrated and described the invention as embodied in a shuttle holding means, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention, and, therefore, such adaptations should and are intended to be comprehended within the meaning and range of equivalence of the following claims.

A loom of the type described above is shown in my U. S. Patent 2,261,296.

What I claim as new and desire to secure by Letters Patent is:

1. A device for holding a shuttle during the changing of the weft bobbin in a loom having a mechanism for automatically changing the weft bobbin and in which the changing of the weft bobbin takes place outside of the shuttle box, comprising, in combination, a resiliently mounted stop engaging one end of said shuttle, the said resiliently mounted stop comprising a spring mounted in a housing, a pin engaging said spring at one end thereof and a picker mounted between said pin and said end of said shuttle; a stop means mounted on said shuttle; and a pawl engaging said stop means on said shuttle, whereby the said shuttle is clamped between said resiliently mounted stop and said pawl so as to fix its position during the changing of the weft bobbin.

2. A device for holding a shuttle during the changing of the weft bobbin in a loom having a mechanism for automatically changing the weft bobbin and in which the changing of the weft bobbin takes place outside of the shuttle box, comprising, in combination, a resiliently mounted stop engaging one end of said shuttle, the said resiliently mounted stop comprising a spring mounted in a housing, a pin engaging said spring at one end thereof and a picker mounted between said pin and said end of said shuttle; a stop means mounted on said shuttle; a pawl engaging said stop means on said shuttle, whereby the said shuttle is clamped between said resiliently mounted stop and said pawl so as to fix its position during the changing of the weft bobbin; a control lever connected to said pawl; and means for turning said control lever so that said pawl is moved out of engagement with said stop means on said shuttle, whereby said shuttle is free to return to its operating position.

3. A device for holding a shuttle during the changing of the weft bobbin in a loom having a mechanism for automatically changing the weft bobbin and in which the changing of the weft bobbin takes place outside of the shuttle box, comprising, in combination, an elongated exchange bearing fixed to said shuttle box; a rail fixedly mounted on said exchange bearing; a first elongated bar slidably mounted in a cutout portion of said rail; a second elongated bar slidably mounted in a cutout portion of said first elongated bar, said first and second bars being located within said shuttle box during the operation of the loom; means for moving said first and second bars out of said shuttle box and along said exchange bearing to a position where the exchange of the weft bobbin takes place; stop means mounted on said first bar for engaging an end of said shuttle so as to determine the position of said shuttle during the changing of the weft bobbin; and means for latching said shuttle in the position where it engages said stop means during the changing of the weft bobbin.

4. A device for holding a shuttle during the changing of the weft bobbin in a loom having a mechanism for automatically changing the weft bobbin and in which the changing of the weft bobbin takes place outside of the shuttle box, comprising, in combination, an elongated exchange bearing fixed to said shuttle box; a rail fixedly mounted on said exchange bearing; a first elongated bar slidably mounted in a cut-

out portion of said rail; a second elongated bar slidably mounted in a cutout portion of said first elongated bar, said first and second bars being located within said shuttle box during the operation of the loom; means for moving said first and second bars out of said shuttle box and along said exchange bearing to a position where the exchange of the weft bobbin takes place; stop means mounted on said first bar for engaging an end of said shuttle so as to determine the position of said shuttle during the changing of the weft bobbin; and means for latching said shuttle in the position where it engages said stop means during the changing of the weft bobbin, the said latching means comprising a pivotally mounted pawl, a groove located in the underside of said shuttle and having a stop surface adapted to engage an end of said pivotally mounted pawl and a control lever connected to said pivotally mounted pawl for moving it into and out of engagement with said groove located in the underside of said shuttle.

5. A device for holding a shuttle during the changing of the weft bobbin in a loom having a mechanism for automatically changing the weft bobbin and in which the changing of the weft bobbin takes place outside of the shuttle box, comprising, in combination, an elongated exchange bearing fixed to said shuttle box, a rail fixedly mounted on said exchange bearing; a first elongated bar slidably mounted in a cutout portion of said rail; a second elongated bar slidably mounted in a cutout portion of said first elongated bar, said first and second bars being located within said shuttle box during the operation of the loom; means for moving said first and second bars out of said shuttle box and along said exchange bearing to a position where the exchange of the weft bobbin takes place and for returning said bars back to their original position within the shuttle box; stop means mounted on said first bar for engaging an end of said shuttle so as to determine the position of said shuttle during the changing of the weft bobbin; and means for latching said shuttle in the position where it engages said stop means during the changing of the weft bobbin, the said latching means comprising a pivotally mounted pawl, a groove located in the underside of said shuttle and having a stop surface adapted to engage an end of said pivotally mounted pawl and a control lever connected to said pivotally mounted pawl for moving it into and out of engagement with said groove located in the underside of said shuttle.

6. A device for holding a shuttle during the changing of the weft bobbin in a loom having a mechanism for automatically changing the weft bobbin and in which the changing of the weft bobbin takes place outside of the shuttle box, comprising, in combination, an elongated exchange bearing fixed to said shuttle box; a rail fixedly mounted on said exchange bearing; a first elongated bar slidably mounted in a cutout portion of said rail; a second elongated bar slidably mounted in a cutout portion of said first elongated bar, said first and second bars being located within said shuttle box during the operation of the loom; means for moving said first and second bars out of said shuttle box and along said exchange bearing to a position where the exchange of the weft bobbin takes place and for returning said bars back to their original position within the shuttle box; a plurality of projections on said first bar; a plurality of por-

tions on said second bar slightly spaced from said projections on said first bar and adapted to engage said projections on said first bar, whereby said second bar moves independently of said first bar until said portions of said second bar engage said projections of said first bar so that said first and second bars then move together; stop means mounted on said first bar for engaging an end of said shuttle so as to determine the position of said shuttle during the changing of the weft bobbin; and means for latching said shuttle in the position where it engages said stop means during the changing of the weft bobbin, the said latching means comprising a pivotally mounted pawl, a groove located in the underside of said shuttle and having a stop surface adapted to engage an end of said pivotally mounted pawl and a control lever connected to said pivotally mounted pawl for moving it into and out of engagement with said groove located in the underside of said shuttle.

7. A device for holding a shuttle during the changing of the weft bobbin in a loom having a mechanism for automatically changing the weft bobbin outside of the shuttle box, comprising, in combination, an elongated exchange bearing fixed to said shuttle box; a rail fixedly mounted on said exchange bearing; a first elongated bar slidably mounted in a cutout portion of said rail; a second elongated bar slidably mounted in a cutout portion of said first elongated bar, said first and second bars being located within said shuttle box during the operation of the loom; means for moving said first and second bars out of said shuttle box and along said exchange bearing to a position where the exchange of the weft bobbin takes place and for returning said bars back to their original position within the shuttle box; a plurality of projections on said first bar; a plurality of portions on said second bar slightly spaced from said projections on said first bar and adapted to engage said projections on said first bar; means for latching said first bar when it arrives at the position where the weft bobbin is changed, the said means comprising a first pawl adapted to engage a cutout portion of said first bar and a portion on said second bar adapted to engage and move said first pawl into and out of engagement with said cutout portion of said first bar; stop means mounted on said first bar for engaging an end of said shuttle so as to determine the position of said shuttle during the changing of the weft bobbin; and means for latching said shuttle in the position where it engages said stop means during the changing of the weft bobbin, the said latching means comprising a pivotally mounted second pawl, a groove located in the underside of said shuttle and having a stop surface adapted to engage an end of said pivotally mounted second pawl and a control lever connected to said pivotally mounted second pawl for moving it into and out of engagement with said groove located in the underside of said shuttle.

8. A device for holding a shuttle during the changing of the weft bobbin in a loom having a mechanism for automatically changing the weft bobbin outside of the shuttle box, comprising, in combination, an elongated exchange bearing fixed to said shuttle box; a rail fixedly mounted on said exchange bearing; a first elongated bar slidably mounted in a cutout portion of said rail; a second elongated bar slidably mounted in a cutout portion of said first elongated bar, said first and second bars being located within said

shuttle box during the operation of the loom; means for moving said first and second bars out of said shuttle box and along said exchange bearing to a position where the exchange of the weft bobbin takes place and for returning said bars back to their original position within the shuttle box; a plurality of projections on said first bar; a plurality of portions on said second bar slightly spaced from said projections on said first bar and adapted to engage said projections on said first bar; means for latching said first bar when it arrives at the position where the weft bobbin is changed, the said means comprising a first pawl adapted to engage a cutout portion in said first bar and a portion on said second bar adapted to engage and move said first pawl into and out of engagement with said cutout portion of said first bar; stop means mounted on said first bar for engaging an end of said shuttle; and means for latching said shuttle in the position where it engages said stop means during the changing of the weft bobbin, the said latching means comprising a pivotally mounted second pawl, a groove located in the underside of said shuttle and having a stop surface adapted to engage an end of said pivotally mounted second pawl and a control lever connected to said pivotally mounted second pawl for moving it into and out of engagement with said groove located in the underside of said shuttle, said control lever comprising a pivotally mounted member adapted to be engaged and depressed by a portion of said second bar.

9. A device for holding a shuttle during the changing of the weft bobbin in a loom having a mechanism for automatically changing the weft bobbin outside of the shuttle box, comprising, in combination, an elongated exchange bearing fixed to said shuttle box; a rail fixedly mounted on said exchange bearing; a first elongated bar slidably mounted in a cutout portion of said rail; a second elongated bar slidably mounted in a cutout portion of said first elongated bar, said first and second bars being located within said shuttle box during the operation of the loom; means for moving said first and second bars out of said shuttle box and along said exchange bearing to a position where the exchange of the weft bobbin takes place and for returning said bars back to their original position within the shuttle box; a plurality of projections on said first bar; a plurality of portions on said second bar slightly spaced from said projections on said first bar and adapted to engage said projections on said first bar; means for latching said first bar when it arrives at the position where the weft bobbin is changed, the said means comprising a first pawl adapted to engage a cutout portion in said first bar and a portion on said second bar adapted to engage and move said first pawl into and out of engagement with said cutout portion of said first bar; stop means mounted on said first bar for engaging an end of said shuttle; and means for latching said shuttle in the position where it engages said stop means during the changing of the weft bobbin, the said latching means comprising a pivotally mounted second pawl, a groove located in the underside of said shuttle and having a stop surface adapted to engage an end of said pivotally mounted second pawl and a control lever connected to said pivotally mounted second pawl for moving it into and out of engagement with said groove, said control lever comprising a pivotally mounted member adapted to be engaged and depressed by a portion of said second bar.

10. A device for holding a shuttle during the changing of the weft bobbin in a loom having a mechanism for automatically changing the weft bobbin outside of the shuttle box, comprising, in combination, an elongated exchange bearing fixed to said shuttle box; a rail fixedly mounted on said exchange bearing; a first elongated bar slidably mounted in a cutout portion of said rail; a second elongated bar slidably mounted in a cutout portion of said first elongated bar, said first and second bars being located within said

10. A device for holding a shuttle during the changing of the weft bobbin in a loom having a mechanism for automatically changing the weft bobbin outside of the shuttle box, comprising, in combination, an elongated exchange bearing fixed to said shuttle box; a rail fixedly mounted on said exchange bearing; a first elongated bar slidably mounted in a cutout portion of said rail; a second elongated bar slidably mounted in a cutout portion of said first elongated bar, said first and second bars being located within said shuttle box during the operation of the loom; means for moving said first and second bars out of said shuttle box and along said exchange bearing to a position where the exchange of the weft bobbin takes place; stop means mounted on said first bar for engaging an end of said shuttle so as to determine the position of said shuttle during the changing of the weft bobbin, said stop means on said first bar comprising a pin engaging a spring at one end thereof and engaging a picker at the other end thereof, the said picker being mounted between said end of said shuttle and said pin, whereby a resiliently mounted stop is provided for said end of said shuttle; and means for latching said shuttle in the position where it engages said stop means during the changing of the weft bobbin.

11. A device for holding a shuttle during the changing of the weft bobbin in a loom having a mechanism for automatically changing the weft bobbin outside of the shuttle box, comprising, in combination, an elongated exchange bearing fixed to said shuttle box; a rail fixedly mounted on said exchange bearing; a first elongated bar slidably mounted in a cutout portion of said rail; a second elongated bar slidably mounted in a cutout portion of said first elongated bar, said first and second bars being located within said shuttle box during the operation of the loom; means for moving said first and second bars out of said shuttle box and along said exchange bearing to a position where the exchange of the weft bobbin takes place and for returning said bars back to their original position within the shuttle box; a plurality of projections on said first bar; a plurality of portions on said second bar slightly spaced from said projections on said first bar and adapted to engage said projections on said first bar; means for latching said first bar when it arrives at the position where the weft bobbin is changed, the said means comprising a first pawl adapted to engage a cutout

portion in said first bar and a portion on said second bar adapted to engage and move said first pawl into and out of engagement with said cutout portion of said first bar; stop means 5 mounted on said first bar for engaging an end of said shuttle and comprising a pin engaging a spring at one end thereof and engaging a picker at the other end thereof, the said picker being mounted between said end of said shuttle and said pin; and means for latching said shuttle in the position where it engages said stop means, the said latching means comprising a pivotally mounted second pawl, a groove located in the underside of said shuttle and having a stop surface adapted to engage an end of said pivotally mounted second pawl and a control lever connected to said pivotally mounted second pawl for moving it into and out of engagement with said groove, said control lever comprising a pivotally mounted member adapted to be engaged and depressed by a portion of said second bar.

12. A device as defined in claim 11 and wherein said pin of said stop means is provided with an extension passing through an opening in a housing in which said spring of said stop means is mounted; and a stop member on said extension located outside of said housing, whereby said stop member limits the movement of said pin by engagement with said housing.

13. A device as defined in claim 12 and wherein a stop means is provided for limiting the movement of said first and second bars toward the position where the weft bobbin is to be exchanged.

14. A device as defined in claim 13 and wherein said second bar is in the form of a rack and said means for moving said first and second bars comprises a pinion in engagement with said second rack bar and a reversible motor operatively connected to said pinion.
